UNITED STATES PATENT OFFICE.

HENRY PRICE BALL, OF NEW YORK, N. Y., ASSIGNOR TO GENERAL ELECTRIC COMPANY, A CORPORATION OF NEW YORK.

CONTROLLING-SWITCH.

No. 831,404.

Specification of Letters Patent.

Patented Sept. 18, 1906.

Application filed February 23, 1905. Serial No. 246,816.

To all whom it may concern:

Be it known that I, HENRY PRICE BALL, a citizen of the United States, residing at New York, county and State of New York, have 5 invented certain new and useful Improvements in Controlling-Switches, of which the following is a specification.

The present invention relates generally to switching apparatus for the distant control 10 of electric motors, and more particularly to the construction of the control-switch and its circuit connections.

The invention is particularly designed for the control of motor-actuated switches such 15 as are employed in breaking high-potential circuits; but it should not be limited to this specific application, since it is capable of use under other circumstances where the motor is to be operated intermittently each time to 20 perform a definite work or to produce a definite range of movement.

In carrying out the invention a double-throw control-switch is connected so as to control a circuit through two parallel 25 branches leading to the motor to be controlled, and other switching mechanism is included in these branches and operated by the motor to close the circuit through one branch and open it through the other at the 30 end of a definite range of movement. With this arrangement the circuit through the motor can be completed only by throwing the control-switch to the proper contacts, and to indicate the condition of this motor-actuated 35 switch mechanism signal-lamps are included in circuit with the parallel branches and are located in proximity to the control-switch. When the motor is employed to produce a definite to-and-fro movement, as in operating 40 a switch, the signal-lamps also indicate the position of the distant switch. This position is also indicated by the position of the control-switch which serves as a check on the lamps.

45 The specific character of the invention will be best understood upon reference to the following detailed description, taken in connection with the accompanying drawings, and its novelty will be specifically pointed 50 out in the appended claims.

In said drawings, Figure 1 is a front elevation of the control-switch. Fig. 2 is a side elevation of the same, showing parts in section; Fig. 3, a rear view of the same, and

Fig. 4 is a diagram illustrating the connections of said switch with the motor and its accompanying control mechanism. 55

Throughout the views like characters refer to like parts.

Referring to the control-switch, 10 designates a suitable support, such as an insulating-panel of a switchboard, upon which the control-switch is mounted, and 11 11^a and 12 12^a designate the fixed switch-contacts, which are mounted on an insulating block or 60 support 13, located at the rear of the panel 10, and secured to a spider 14 by suitable bolts 15. This spider is in turn secured to a thimble 16, which extends through an aperture in the support 10 and terminates at its 65 front in threaded engagement with the face-plate 17, which is held against movement by suitable bolts 18. The contacts 11 11^a and 12 12^a are adapted to be connected by a bridging contact 19, secured to an insulating 70 block or head 20, mounted on the rear end of a rod 21, which extends through the thimble 16 toward the front of the support 10. The forward end of the rod 21 is connected by a 75 link 22 to the end of an operating-lever 23, which is pivoted at the point 24 to a swiveled support 25, which comprises a tubular portion 26, which extends into the thimble 16, and two laterally-projecting arms 27, to the 80 outer ends of which the operating-lever 23 is pivoted. This lever, which is provided with a handle 28, when rotated with its support 25 causes the bridging contact 19 to be 85 similarly rotated, and the movement of the parts in either direction is limited by the engagement of the projection 29 on the lever 23 with the limiting-stops 30, mounted on the 90 face-plate 17. These stops are located so as to stop rotation when the bridging contact 95 has reached a position in line with either set of contacts 11 11^a or 12 12^a. It will be noted that this rotation of the operating-lever does not bring the switch-contacts into 100 engagement, because of the length of the connecting-rod 21 and its connecting-link 22. To bring about this engagement, the operating-lever 23 is rocked about its pivot 24 toward the support 10, so as to bring the handle 28 to the dotted-line position shown in Fig. 2. In order to prevent this movement except 105 when the bridging contact 19 is in line with either set of fixed contacts, the space between the stops 30 on the face-plate 18 is provided

with a projecting rib 31, which engages the projection 29 on the operating-lever and prevents its movement into the dotted-line position. This rib does not extend the entire distance 5 between the stops 30, but stops short thereof, leaving a slot or depression adjacent each stop for the passage of the projection 29 when the handle 28 is forced inward. To return the contact 19 to its open position, a 10 coiled spring 32 is provided. This spring bears at one end against the spider 14 and at the other against an armature 33, which abuts the insulating-head 20. The armature 33 is composed of suitable magnetic material and coöperates with the electromagnet 34 to hold the switch-contacts in engagement without the continued application of force to the operating-lever 23. This magnet comprises an annular core 35, of iron or other suitable 15 magnetic material, which is part of the spider 14, and an energizing-coil 36, associated therewith. A plate 37 is provided on the pole-faces to keep the armature from sticking.

20 Referring to the diagram shown in Fig. 4, the contacts 11^a 12^a are connected in series with the coil 36 and to one leg 38 of the supply-circuit. The other contacts 11 and 12 are connected, respectively, in series with indicator-lamps 39 and 40 to a common lead 41, 25 also connected to the leg 38 of the supply-circuit. A suitable resistance 42 is interposed in the lead 41, so as to cut down the current to an amount suitable for the indicator-lamps 39 40. The other leg 43 of the supply-circuit is connected by a lead 44 to armature 45 of the motor to be controlled, and the circuit from the armature is completed through the field-winding 46 to the fixed contacts 47 30 of two motor-controlled switches R R', whose movable elements are electrically connected to the contacts 12 and 11, respectively. The switch-blades 49 and 50 are controlled by cams 51 and 52, actuated by the motor-armature 45, and these cams are shaped so as to maintain one switch, as R, open, and the other, as R', closed during 35 a definite movement of the motor. When this movement is completed, the switch R' is closed, and substantially simultaneously therewith the switch R is opened. With this organization it will be seen that there is always one circuit completed through the motor, and by throwing the control-switch to the 40 proper position the motor can be started to operate through its given range of movement. For instance, assuming that the parts as illustrated are at rest, it will be apparent that if the control-switch is thrown so as to complete 45 the circuit between the contacts 11 and 11^a a circuit will be completed from the leg 38 of the supply through the lead 41, resistance 42, lamp 39, contact 11, through one branch, and from the same leg 38 through the 50 branch including the magnet-coil 36 to con-

tact 11^a, thence to contact 11, where the two branches combine and the circuit is completed through the switch-contacts 50 48, field-winding 46, armature 45, and lead 44, to the other leg of the supply-circuit. This will 70 be sufficient to set the motor rotating, and as it rotates it will maintain the circuit through the switch R' until the cams have moved far enough to allow the contact-arm 50 to drop away and to force the contact 49 into engagement. This will break the motor-circuit, and thus stop the motor and at the same time will leave the other branch circuit in condition to be closed by the control-switch. In 75 this operation while the motor is rotating current will be supplied to the lamp 39, and as soon as its rotation ceases and the contacts 47 and 49 are brought together the lamp 40 will be lighted. If the motor is designed to operate a switch S, as is diagrammatically 80 shown, the particular lamp lighted will indicate whether or not the switch is open or closed. In this operation when the operating-lever 23 is thrown to the right or left in order to bring the movable contact 19 into 85 line with the proper set of fixed contacts and is then forced inward toward the support 10 to bring the contacts into engagement the circuit through the retaining-magnet coil 36 will be completed, and the armature 33 will 90 be held against the face of the magnet and the contacts maintained in engagement until the motor has completed its range of movement and the circuit through the coil 36 is broken by the switch mechanism controlled 95 by the motor. The position of the operating-lever will indicate which way the double-throw switch was last thrown by its position to the right or left and also the condition of the motor mechanism and the switch S by its 100 position relative to the support 10. When the lever-handle is near the support—as, for example, in the dotted-line position in Fig. 2—it will indicate that the motor is still in operation, and when it is most distant from the 105 support it will show that the motor has ceased to operate.

To one skilled in the art it will be apparent that certain alterations and modifications may be made in the matter illustrated 110 without departing from the spirit and scope of the invention. I therefore do not wish to be limited to the specific matter disclosed, but aim to cover by the terms of the appended claims all such alterations and modifications.

What I claim as new, and desire to secure by Letters Patent of the United States, is—

1. The combination with an electric motor, of two parallel circuits including said motor, a manual switch for severally closing said parallel circuits biased to open when closed, means operated by the closing of one of said parallel circuits to hold said switch closed, and means actuated by the motor to break 125

130

the circuit last manually closed and place the other in condition to be closed by said manual switch.

2. The combination with an electric motor, of two parallel circuits including said motor, a manual switch for severally closing said parallel circuits, a spring normally tending to open said switch, means operated by the closing of one of said parallel circuits to hold said switch closed against the action of said spring, and means actuated by the motor to break the circuit last manually closed and place the other in condition to be closed by said manual switch.

15 3. The combination with an electric motor, of two parallel circuits including said motor, a manual switch for severally closing said parallel circuits biased to open when closed, electromagnetic means energized by the closing of one of said parallel circuits to hold said switch closed, and means actuated by the motor to break the circuit last manually closed and place the other in condition to be closed by said manual switch.

25 4. The combination with an electric motor, of two parallel circuits including said motor, a manual switch for severally closing said parallel circuits, a spring tending to open said switch, an electromagnet energized by the closing of one of said parallel circuits to hold said switch closed against the action of said spring, and means actuated by the motor to break the circuit last manually closed and place the other in condition to be closed by

35 said manual switch.

5. The combination with a main switch, of an electric motor for operating said switch, two parallel circuits including said motor, a manual switch for severally closing said parallel circuits biased to open when closed, means operated by the closing of one of said parallel circuits to hold said switch closed, means actuated by said motor to break the circuit last manually closed and place the other in condition to be closed by said manual switch, and indicator-lamps included in said parallel circuits for showing the condition of said motor-actuated means and said main switch.

50 6. A double-throw electric switch biased to open when closed, means for holding said switch in either closed position for a definite time, and means for indicating which way the switch was last thrown.

55 7. A double-throw electric switch biased to open when closed, means for holding said switch in either closed position for a definite

time, and means for indicating which way the switch was last thrown and whether it is open or closed.

60

8. A double-throw electric switch biased to open when closed, means for holding said switch in either closed position, means for releasing said holding means, and means for indicating which way the switch was last thrown.

65

9. A double-throw electric switch biased to open when closed, means for holding said switch in either closed position, means for releasing said holding means, and means for indicating which way the switch was last thrown.

70

10. In an electric switch, the combination with two sets of fixed contacts, of a co-operating movable contact, an operating-lever movable in one direction to bring said movable contact into line with one set of fixed contacts and movable at an angle to said direction to bring said contacts into engagement, and means mounted to engage the operating-lever to prevent the latter movement except when said contacts are in line.

75

11. In an electric switch, the combination of fixed and movable contacts, a rotary reciprocating member carrying the movable contact, a movable support pivoted concentrically with said member, and an operating-lever secured to the end of said member and pivoted at an intermediate point to said support.

80

12. In an electric switch, the combination with fixed and movable contacts, of a rotary reciprocating member carrying the movable contact, a spring tending to maintain said contacts out of engagement, and an electromagnet for holding said contacts in engagement against the action of said spring.

85

13. The combination with a supporting-base, of fixed contacts mounted on the rear thereof, a rotary reciprocating member extending through an opening in said base, a movable contact carried thereby, an operating-lever for rotating and reciprocating said member mounted at the front of said base, and a retaining-magnet for said reciprocating member mounted adjacent to said fixed contacts.

90

In witness whereof I have hereunto set my hand this 20th day of February, 1905.

HENRY PRICE BALL.
